UNITED STATES PATENT OFFICE

2,648,963

KNITTED WARE AND METHOD OF
PRODUCING SAME

Henry Harold Holmes, Leicester, England, assignor to Wildt and Company Limited, Leicester, England, a British company

Original application August 8, 1947, Serial No. 767,546. Divided and this application May 3, 1948, Serial No. 24,857. In Great Britain March 27, 1939

Section 1, Public Law 690, August 8, 1946
Patent expires March 27, 1959

8 Claims. (Cl. 66—180)

1

This invention relates to knitted ware, which term includes both fabric and articles, and to a method of producing the same. The present application is a division of application Serial No. 767,546, filed August 8, 1947, and now abandoned.

The invention has reference more particularly to rib knitted ware of the kind comprising a structure of loops composed of a ground yarn or yarns and patterned by plating effects in which a wrap thread or threads is or are knitted on the face of the said structure.

One object of the invention is to provide, in the plain knitted panels of rib knitted, more particularly broad rib, ware improved wrap designs as will be hereinafter described.

Another object is the provision of rib knitted fabric and articles having pattern effects produced by what may conveniently be called "panel wrapping" in colour over colour designs. In this respect the invention includes within its scope rib knitted ware in which at least the endmost knitted loops of courses in all the plain knitted panels thereof are intermeshed with wrap stitches.

In panel wrapping, a single wrap thread, fed by a suitable guide, is presented to a group of plain needles and taken and knitted by any selected needle or needles, or by all of the needles, of the said group, according to patterning requirements.

In the accompanying drawings,

Figure 1 is a back view, drawn to a greatly enlarged scale, of a portion of broad rib fabric patterned in accordance with this invention.

Figure 2 represents a half-hose including a patterned broad rib leg and instep, as will be hereinafter described.

Figure 3 is a vertical sectional view of so much of a circular knitting machine of the superimposed cylinder type as is necessary to illustrate some of the mechanism necessary to carry out the aforementioned method.

Figure 4 is a fragmentary view showing a group of plain needles and the manner in which they are selected to receive a wrap thread presented thereto.

Figure 5 is a vertical sectional view of the upper portion of the machine showing the selector mechanism both for the wrap thread guides and for shogging the latter, for the purposes hereinafter to be described.

Figure 6 is a side elevational view, partly in section, showing the mechanism whereby the wrap thread guides can be shogged bodily in a circumferential direction relatively to the needles,

2

Figure 7 is a plan view, partly in section, corresponding to and looking in the direction of the arrow in Figure 6 and showing, in addition, the top needle cylinder of the machine and the cylindrical carrier for the wrap thread guides,

Figure 8 is a detail sectional plan view taken on the line VIII—VIII of Figure 5,

Figure 9 is a side view of one of the thread guides per se,

10 Figure 10 is an enlarged detail view showing the lower portion of a guide with its thread wrapped around a needle,

Figure 11 is a diagrammatic plan view including a layout of a few of the groups of needles 15 of the machine and associated wrap thread guides, a deflector for moving the thread guiding portions laterally at appropriate times and a needle selecting arrangement, and

Figures 12-16 are detail plan views illustrating 20 in purely diagrammatic fashion different stages of a thread wrapping operation in which active and inactive wrap thread guides are employed.

Like parts are designated by similar reference characters throughout the drawings.

25 The portion of fabric depicted in Figure 1 comprises multi-wale panels R of inwardly facing rib knitted loops alternating with multi-wale panels P¹, P² and P³ of outwardly facing plain knitted loops. The fabric is a 6 x 3 broad rib

30 and includes two courses a and b of 1 x 1 rib. At course d in the central panel P² there is included a wrap thread W¹ which is knitted into wales 3 and 4 and thereupon floated at the back of the fabric to course e where it is knitted into wales 1, 2, 5 and 6. From thence the wrap thread W¹ is again floated at the back of the fabric to course f where it is knitted into wales 2 and 5. After being floated to course g the said thread is knitted in all wales 1-6 inclusive.

35 At this stage the wrap thread W¹ is floated in an inactive position, and another wrap thread W² is introduced in panel P² at course h, in substitution for the thread W¹, and is knitted in wales 1-6 inclusive. The thread W² is now floated at the back of the fabric, and, after being

40 knitted in course i on wales 2 and 5, is again floated at the back of the fabric, with the wrap thread W¹, for subsequent inclusion in the fabric. Thus it will be appreciated that in

45 the plain knitted panel P² each of the wrap threads W¹ and W² may, according to the design, be included in any of the knitted wales at each of desired courses of the panel, including the two endmost wales immediately adjoining

50 the adjacent rib panels R. In the panel P¹, a

55 the adjacent rib panels R. In the panel P¹, a

wrap thread W^3 , shown in course d , is knitted into wale 1 and, after being floated at the back of the fabric for inclusion in other loops (not shown), is knitted into wale 2 of course e and wales 1 and 3 of course f . The wrap thread W^3 is also knitted into the said wale 1 at each of the subsequent courses g and h . In a similar way a further wrap thread W^4 is knitted into various loops including those in wale 1 at courses h , i and j . Similarly, the wale 6 of panel P^3 has wrap threads W^5 and W^6 knitted thereinto.

The wrap threads of the pairs W^1 and W^2 , W^3 and W^4 and W^5 and W^6 may contrast, e. g. as regards colour.

In Figure 2 there is shown a seamless half-hose comprising a welt 9, a 1/1 ribbed top 10, a ribbed leg 11, a similarly ribbed instep 12, said leg and instep being of an appreciably broader rib than the top 10 and patterned in accordance with this invention, a plain knitted and non-patterned foot bottom 13 and a plain heel 14 and toe 15. The leg and instep may be 6/3 rib, comprising panels P of six plain knitted wales in width alternating with groups F of three rib knitted wales. Each of the plain knitted panels P is patterned with panel wrap striping effects such as 16 and 17 which may be designs of the character illustrated in Figure 1. For instance, each of the designs 16 may be produced from one wrap thread whilst each of the designs 17 may be produced from another such thread.

The machine illustrated in Figures 3 and 5 includes rotary bottom and top cylinders 20 and 21 respectively equipped with double-ended needles 22 and associated needle-operating sliders. The sliders in the bottom cylinder are indicated at 23 (see Figure 3), but those customarily provided in the top cylinder have been omitted for convenience in illustration. The bottom cam box is represented at 24 and top cam box at 25. The machine is furnished with thread wrapping mechanism including thread guides 26 in the form of blade-like elements each provided with a thread guiding portion 27 which extends at an angle, e. g. at right angles, from the main portion of the blade or like part, said guides being mounted in a cylindrical bed 28 so as to extend in an axial direction or substantially so with respect to the needle cylinders, for movement radially across the needle circle from the inside to the outside and vice versa.

For the purpose of producing the improved knitted ware the needles 22 of the machine are set out to provide spaced groups of plain needles for operation in the bottom cylinder 20 alternating with groups of rib needles for operation in the top cylinder 21. The thread guiding portions 27 of the thread guides 26 are fashioned and mounted so as to be adapted to pivot or swivel laterally under spring control as will be hereinafter more fully described, and a deflector 29 in the form of a cam or an abutment is so formed and arranged adjacent to such thread guiding portions that when the guides are projected radially from their normal position said portions are engaged by the deflector and deflected laterally to the extent of an entire group of plain needles. In this form of the invention the deflector 29 is in a common position to all of the guides 26 and lateral deflection or swivelling movement of the portions 27 seriatim is engendered by the rotational movement of the series of guides and the deflector 29 one in relation to the other. Thus, since the machine being described is a revolving cylinder machine, lateral deflection or swivelling move-

ment of the thread guiding portions 27 is engendered, in this particular example, by the rotational movement of the guides 26 in company with the needles 22, in relation to the deflector 29.

Concerning the actual form and construction of the thread guides 26, each of these is conveniently adapted to pivot or rock about a fulcrum point 30 and, as shown more clearly in Figure 9, has on its flat, main, axially extending portion a frontal (pressure) butt 31, a main butt 32 and an upwardly extending butt 33. At its lower extremity the said main portion is cut at 34 in the manner represented in Figure 10 and a part thereof is pressed out laterally and turned down suchwise as to provide an integral flat lug 35. This lug therefore projects from one side of the guide, and constitutes as it were a bracket or support for a small vertically disposed pin 36. This pin is bent over at its upper end so as to make contact with the adjacent side face of the thread guide, while the lower portion of the pin extends through and beneath the lug 35. The aforesaid thread guiding portion 27 is for the most part straight and is provided at its inner end with a bush or sleeve 37 adapted to fit and turn upon the pin 36. Provision of any suitable character may be made to prevent axial displacement of the portion 27 from the pin. The construction is therefore such that the thread guiding portion can pivot or swing on the pin 36. The lower end of the main portion extends at right angles to the remainder thereof and in this way is adapted to present a relatively inflexible stop or abutment 38 against which the pivotal thread guiding portion 27 is normally pressed by means of a torsion spring 39. This spring is arranged to surround the pin 36 with one end thereof bearing upon the main portion and its opposite end upon the pivotal portion 27 as shown in Figure 10. Accordingly, lateral movement of the portion 27, when required, is effected against the action of the spring 39. At or near its outer end the pivotal thread guiding portion of each guide 26 may conveniently be formed with a downwardly directed extension 40 which is provided with one or more, e. g. a pair of, eyes such as 41 for reception of a wrap thread W .

It has previously been mentioned that the guides 26 are projected radially to enable them to be engaged by the deflector 29. In this particular example the projection of the guides for this purpose is in an outward direction across the needle circle from the inside to the outside. In this connection, a bank of selector levers or cams 42 (Figure 5) is provided for action selectively upon the pressure butts 31, so that selected guides are pressed inwards at their upper ends and thereby projected radially at their lower ends. The machine is also furnished with a retracting cam 43 arranged for action upon the upwardly extending butts 33 seriatim for the purpose of restoring selected guides to their normal position. The arrangement is such that after a selected thread guide 26 has been projected radially outwards into the path of the deflector, and while the corresponding pivotal thread guiding portion 27 is still deflected, the said guide is caused to revert to its normal position, i. e. it is moved radially inwards back across the needle circle—this time from the outside to the inside—thus being brought out of contact with the deflector 29 so that the thread guiding portion springs back to its original position in relation to the needles served by the guide.

Means are also provided for effecting appropriate relative lengthwise movement of the nee-

dles 22 and guides 26 so that by reason of such movement and the conjoint lateral deflection of the thread guiding portions 27 the threads W furnished by the guides may be wrapped about all of the needles in the groups of plain needles served by the respective guides. In this connection either the needles may be moved towards the guides or the latter may be moved towards the needles, or both the needles and the guides may be moved lengthwise, appropriate cam or equivalent means suitably disposed being provided for this purpose in conjunction with cam means for imparting reverse movement to the needles or/and guides after the wrapping action. In the specific example illustrated the needles 22 are moved lengthwise, and such movement of the needles is taken advantage of to move them selectively so that in any group of two or more plain needles served by a guide, one or any one of the group of said needles may be caused to knit the thread supplied by the guide, while the other or others do not. This last mentioned result may conveniently be achieved by initially moving both or all of the needles in each group to a favourable position to receive the thread supplied by the associated guide, and thereafter imparting further movement to a selected needle or needles suchwise that when such needle or needles is or are ultimately retracted and caused to knit, the thread passes idly over the needle hook or hooks without being formed into a wrap stitch or stitches. The manner in which needles are selected to receive a wrap thread will be clear from a consideration of Figure 4 wherein of the group of six plain needles 22 shown, the first, third, fourth and sixth needles have been positioned to take the thread W so that the second and fifth needles of the said group will miss this thread.

The selection of the needles in this way may be effected by means of a needle selecting arrangement or pattern controlled variable needle selecting means of any suitable type. Thus, as shown in Figures 3 and 11, the said means may comprise a bank of cams 44 controlled by a pin drum 45 (see Figure 11) having therein removable pins 46 which act upon intermediate levers 47 pivoted individually on a spindle 48. The levers 47 engage the cams 44 to render same operative or inoperative. In Figure 3, the topmost cam 44 is operative, the other cams beneath it being inoperative. The pin drum 45 may conveniently be racked round by means of a pawl and ratchet mechanism (not shown). The cams 44 are slideable radially with respect to the bottom needle cylinder 29 in a bracket 49 mounted on the machine bed. As will be understood, the said cams act selectively upon patterning butts 50 (Figure 3) of the sliders 23, there being as many butt positions as there are cams but not in every case a full complement of butts on each slider, butts being broken off the sliders according to pattern requirements. The bank of selecting cams 44 is located adjacent to a knitting cam system of conventional form in the bottom cam box 24. When any one of the cams is rendered operative by being advanced towards the needle cylinder 29 by a lever 47 acted upon by a pin 46 in the drum 45 a slider or sliders having a corresponding butt or butts is raised by reason of the cams being obliquely disposed, and the corresponding needle or needles is or are advanced somewhat. The remaining sliders are not affected and consequently their needles function in the normal way. With regard to the aforesaid lengthwise movement of the thread guides 26, a track cam 75

51 (see Figure 5) is provided for action on the main butts 32 seriatim, the formation of the track being such that at the wrapping stations the guides are correctly positioned for wrapping. 5 As already alluded to herein there may be two or more thread guides 26 for each group of plain needles, and these guides may be selectively operated so that either or any one of them may be caused to serve the needles or any needle of the group. Moreover, by making provision whereby the cylindrical carrier 28 for the thread guides can be shogged bodily in a circumferential direction relatively to the needles to the extent of a suitable number of a group of plain needles, it is possible by first effecting a required shogging movement to displace the guides angularly to a desired extent and thereupon selectively operating the said guides to substitute one wrap thread for another for presentation to any or all of the plain needles of a particular group. That is to say, assuming that there are two guides for each group of plain needles and that one of these two guides is in operation whilst the other is idle, then by shogging the whole series of guides and selectively operating the same the idle guide of the two concerned can be displaced angularly to the common feeding position in relation to the said group of plain needles and thereby substituted for the other guide whilst the latter is simultaneously moved to its non-feeding position. This will be clearer from a consideration of Figures 12-16. In Figure 12 there is depicted a portion of a verge ring 66 (which ring is fully shown in section in Figure 3), and two thread guides 26 of which the hinged thread guiding portions 27 are shown in plan with threads W¹ and W² fed by these guides floating behind a group 67 of six plain needles. Groups 68 each 40 of three rib needles are shown adjacent to the opposite sides of the group 67 of plain needles. Of the two thread guides the one indicated at O is in the common wrap thread feeding position whilst the other thread guide indicated at I is idle. At the stage illustrated in Figure 13 45 the operative thread guide at O has been selected so that its thread guiding end 40 is projected between the last rib needle of a group 68 and the first plain needle of a group 67. This projection of the said guide takes place in advance of the deflector 29, it being understood that the series of thread guides and the needles of the machine are travelling together in the direction of the arrow indicated. Referring now 50 to Figure 14, the thread guiding portion 27 of the operative thread guide at O has, by reason of contact with the deflector 29, been deflected laterally to an extent sufficient for the thread W¹ to have been taken by the first four plain needles of the group 67, the thread guide at I still remaining idle with its wrap thread W² floating behind the needles. At the next stage shown in Figure 15, the thread guiding portion 27 of the operative thread guide at O 55 has completed the wrapping of the group 67 of plain needles and is in the course of being retracted to the inside of the needle circle between the last plain needle of the group and the first rib needle of the adjoining group 68. At this stage the said thread guiding portion 60 has, by reason of continued travel of the thread guides and needles in the direction indicated, left the deflector 29. In Figure 16 all of the thread guides, including both those in an operative position O and also those in an idle position I,

are fully retracted. Successive stages of a complete wrapping action of one of the operative thread guides are indicated in chain lines. It will be noted that at the position D, that is to say at the termination of its wrapping action, an operative guide will contact the end of an idle guide and deflect it against its spring action, this, however, being in no way detrimental. Rib knocking over bits mounted in the verge ring 66 are shown at 69 in Figure 16. When it is required to substitute the operative guides at O for the idle guides at I, angular displacement of the whole series of guides, relatively to the needles, to the extent of the angle α , i. e. the pitch of the guides, is effected by the shogging mechanism hereinafter to be described with reference to Figures 5, 6 and 7.

For selection of the thread guides selector levers or cams 42 are, as hereinbefore alluded to, provided for action selectively upon the appropriately distributed pressure butts 31. These selector levers or cams are adapted to be rendered operative and inoperative under the control of a drum 52 which is included in a pattern device or unit hereinafter to be described.

The deflector 29 may occupy a fixed position both circumferentially and radially with respect to the thread guides 26 so that wherever a guide is rendered operative the thread guiding portion 27 thereof is deflected as a matter of course. The deflector 29 is adapted for sliding movement radially within a bracket 53 attached to the top of the cam box 24 and is controlled by a tension spring 54. One end of this spring is anchored to the bracket 53 while the opposite end thereof is anchored to a pin 55 carried by the deflector 29. The operative, i. e. innermost, position of the deflector is determined by a screw abutment 56 which is carried by the enlarged outer end 57 of said deflector and adapted at its leading end to make contact with an appropriate part of the bracket 53. By suitable adjustment of the screw abutment 56 the innermost position of the deflector can be carried within limits. A lever 58 adapted to be controlled by or from the main controlling or timing mechanism of the machine is provided for operating the deflector according to requirements. The operative extremity of this lever is arranged to press upon the outer end of the deflector (see Figure 3), the arrangement being such that the latter is pressed into its operative position against the spring action and permitted to return at appropriate times to a normal inoperative position under said action. In any event, the deflector may be in the form of a cam having an operative edge or face 59 appropriately shaped (for instance as represented in Figures 11 and 13-16) and positioned in the manner shown with respect to the path followed by the thread guiding portions of any thread guide moved radially in advance of the group of plain needles to be served, so as to hold the engaged guide deflected for the appropriate length of time.

The cylindrical carrier 28 for the guides 26 is rotatably mounted upon a sleeve 60 depending from the top plate 61 of the machine. The wrap striping threads W may be guided from bobbins, cones, spools or reels mounted upon a rotary bracket through tubes 62 appropriately assembled within the sleeve 60. The customary gear ring 63 on the top cylinder 21 is furnished with grooved securing segments 64. A gear ring 65 is arranged normally to drive the cylindrical

carrier 28 at the same speed as the top cylinder 21.

The aforementioned means for shogging the thread guides 26 bodily in a circumferential direction relatively to the needles 22 is of the character described in prior United States Patent No. 2,065,469. This mechanism is employed as and when required to drive the cylindrical carrier 28 independently. Broadly considered, 10 said shogging mechanism comprises a pinion 70 freely mounted upon the top cylinder driving shaft 71. The pinion 70 is driven by a reel 72 slidably keyed on the shaft 71 and having opposed steeped cams 73 and 74 radially offset and engaged by rollers 75 and 76 on a pattern controlled slide 77. The reel 72 also has a driving dog 78 with stepped edges 79 to engage opposed screws 80 arranged on the underside of the pinion 70. The screws 80 are carried by 20 slidable bars 81 which are adjustable so that the amount of shogging for a predetermined movement can be varied. A gear 82 which is rotatable with the shaft 71 meshes with the teeth on the gear ring 63 and the pinion 70 meshes 25 with the teeth on the gear ring 65. With this arrangement, therefore, the cylindrical carrier 28 can either be driven from and at the same speed as the top cylinder 21 (as it would normally be), or it can be shogged in either direction to the extent required by appropriate axial movement of the reel 72 upon the shaft 71.

It is convenient here to mention that the structure serving to support the aforesaid bobbins, spools, cones or the like is mounted upon 35 a rotary toothed part 83 which is adapted to mesh with and thereby be driven by a gear wheel 84 in turn driven by the shaft 71.

The shogging mechanism may conveniently be adapted to be controlled by the same pattern device or unit as that which is used selectively to 40 operate the selector levers or cams 42. The pattern device or unit shown is of the general character described in prior United States Patent No. 2,196,073. As will be seen, the said device or unit comprises two drums 52 and 85, one fixedly 45 and the other freely mounted co-axially on a hollow spindle 86 in turn rotatably mounted on a fixed axle 87. The freely mounted drum 52 is formed with a neck 88 having a radial lug 89. The spindle 86 has keyed thereon ratchet wheels 90 and 91 arranged so as to enable forward or reverse rotation to be imparted to the spindle according to requirements. The ratchet wheel 90 is connected with the neck 88 by an arrangement comprising, in combination, a pair of arcuate blocks 92 (see Figure 8) located in a circular groove 93 in the wheel, one on each side of the lug 89, a tension spring 94 engaged with a pair of screws 95 one in each block at the end opposing the lug 89, a pair of screws 96 one inserted in each block at the other end, and a pair of plates 97 attached to the ratchet wheel 90 in the positions shown in Figure 8. The drum 52 has a toothed ring 98 attached to it, and a catch 99 is urged into engagement with said ring so as normally to prevent rotation of the drum. The catch 99 is operated by any suitable means in 55 timed relation with the operative strokes of pawl and ratchet mechanism by means of which the spindle 86 is racked round. The arrangement is such that normally the spring 94 pulls the nearby ends of the blocks 92 up against the lug 89. When the ratchet wheels 90 and 91 are racked in either direction the drum 85 is racked to a 60 corresponding extent and the spring 94 is ten- 65

sioned so long as the freely mounted drum 52 is held by the catch 99. Consequently when said catch is operated to release the drum 52 the latter is racked by the spring 94. The two drums are therefore racked one after the other. As herein alluded to, the drum 52 is utilised for controlling selective operation of the thread guides, 26, while the other drum 85 is employed to effect or control shogging of said guides relatively to the needles. Both of the drums are adapted to receive pins or pegs, those 100 in the drum 52 being for action upon the selector cams or levers 42, and those such as 101 in the drum 85 for action on a lever 102. The lever 102 may be pivoted and adapted to effect through any suitable intermediate mechanism (not shown), movement of the slide 77. A spring-pressed disc 103 is adapted to act frictionally on the bottom of the drum 85 to prevent the latter from over-running when racked round. The disc 103 is held down by an intermediate member 104 which is in turn acted upon by compression springs such as 105.

The slide 77 is mounted for movement horizontally and at its inner end is formed with an extension 106 on which the rollers 75 and 76 are mounted so as to be located in different vertical and horizontal planes. The corresponding steps of the cams 73 and 74 are off-set with respect to each other in a radial direction on the reel to suit the positions of the rollers 75 and 76 so that each is enabled to be acted upon by its respective cam.

Each of the slidable bars 81 is mounted for adjustment inwards and outwards radially in relation to the axis of the pinion 70 so as to enable the degree of turning movement effected by a predetermined adjustment of the slide 77 to be varied. Referring to Figures 6 and 7 it will be seen that the upper edges of the slidable bars 81 are received in longitudinal guideways 107 formed in the underside of the pinion 70 and are adapted to be clamped to the sides of a rectangular block 108 formed integrally with said pinion by means of screws 109. To permit of the lengthwise adjustment of the slidable bars 81 the latter are formed with longitudinal slots 110—one for each screw 109.

Means of any appropriate character may be provided for restricting the wrap striping action to a particular area or areas of the knitted fabric or article, as for example in the production of seamless hosiery such as the article shown in Figure 2 and/or for entirely nullifying said action, as for example in a seamless hosiery machine during reciprocatory knitting or the production of a 1x1 rib top. In the specific machine illustrated in Figures 3 and 5, the pattern device or unit (shown in Figure 5) may for this purpose be arranged for swinging movement bodily away from the thread guides at appropriate times. In any event the control may be from the existing timing or control mechanism of the machine or from an auxiliary mechanism through intermediate means of any conventional character.

Spring or spring controlled thread take-up elements or means may be provided, e. g. one for each wrap thread.

As will be appreciated, by the use of a machine equipped with the mechanism herein before described it is possible to produce all manner of panel wrapping designs in which a single wrap thread is included in any selected knitted loop or loops, or in all of the loops, of the same course, in a plain knitted panel. Since all the plain

needles of a group are within the lateral extent of the wrapping action of a relevant thread guide, selection of the said needles from course to course will naturally afford the possibility of obtaining any design. Moreover, the mechanism described enables such designs to be produced in successive plain knitted panels, with, if desired, wrap effects included in the endmost knitted loops of the said panels. This is made possible by the use of a deflector the operative end (such as 59) of which is stationary in relation to the circumferential movement of the series of thread guides. Thus, referring to Figure 16, it will be seen that the hinged thread guiding portion 27 of a thread guide 26 is not brought into contact with the deflector 29 until the latter is opposite the space between the last rib needle of the rib panel 68 immediately preceding the panel 67 of plain needles to be wrapped and the first of said plain needles and is not disengaged from contact with the deflector 29 until, by reason of its deflection, it is positioned between the last plain needle of the said group 67 and the first rib needle of the panel 68 on the opposite side of the group 67.

What I claim then is:

1. Broad rib knitted ware comprising multi-wale panels of inwardly facing rib knitted loops alternating with multi-wale panels of outwardly facing plain knitted loops, and a plurality of wrap threads each of which is included in all the plain knitted loops, including the two endmost loops, in the same course, in a plain knitted panel that is at least four wales wide, the groups of wrapped loops being thereby separated, coursewise, to the extent only of one rib knitted panel.

2. The method of knitting comprising the steps of reversely drawing loops in a course so as to produce spaced multi-wale panels of inwardly facing rib knitted loops and intervening multi-wale panels of outwardly facing plain knitted loops, and interknitting a wrap thread with a plurality of loops in the same course, including at least the two endmost loops, coursewise, of a plain knitted panel having a width of at least four wales.

3. The method of knitting comprising the steps of reversely drawing loops in a course so as to produce spaced multi-wale panels of inwardly facing rib knitted loops and intervening multi-wale panels of outwardly facing plain knitted loops, and knitting a wrap thread with any of the adjacent loops of a course in each of the plain knitted panels including the two endmost loops, coursewise, of said panels so as to produce wrap effects separated, coursewise, by the rib panels only.

4. In a method of knitting a circular seamless article of footwear comprising knitting a top portion, a broad-ribbed leg and instep portion and integral heel, sole and toe portions, said leg portion being knit of body yarn with groups of outwardly facing stitches forming face panels separated by inwardly facing stitches forming rib wales, the improvement that comprises knitting a wrap yarn in plating relation with the body yarn in a plurality of stitches in the same course of a face panel in each of a plurality of successive courses including stitches immediately adjacent said rib wales to form a wrap design extending in a coursewise direction to the edges of said face panel.

5. Broad rib knitted ware comprising multi-wale rib panels of inwardly facing rib knitted

loops alternating with multi-wale plain panels of outwardly facing plain knitted loops, and at least one wrap thread included in the same course in at least the two endmost wales of a plain knitted panel having a width of at least four wales, so that wrap effects appear in wales immediately adjoining the rib panels on opposite sides of said plain panel.

6. Broad rib knitted ware comprising multi-wale panels of inwardly facing rib knitted loops alternating with multi-wale panels of outwardly facing plain knitted loops, said plain panels being at least four wales wide, and a plurality of wrap threads incorporated in successive plain knitted panels to form wrap stitch effects, each of said wrap threads being incorporated in a plurality of stitches in the same course in a plain panel, including stitches in the end wales of said plain panel, so that the wrap stitch effects in successive plain knitted panels are separated to the extent of one rib panel only.

7. Broad rib knitted ware comprising multi-wale rib panels of inwardly facing knitted loops alternating with multi-wale plain panels of outwardly facing plain knitted loops and at least one wrap thread included in a plurality of stitches in the same course of a plain panel of at least four wale width, the wrap yarn being in-

cluded in the first and last wales of said plain panel to form a wrap pattern that extends from edge to edge of said plain panel.

8. The method of knitting a broad ribbed fabric comprising the steps of reversely drawing loops in a course so as to produce spaced multi-wale panels of inwardly facing rib knitted loops and intervening multi-wale panels of outwardly facing plain knitted loops, incorporating at least one wrap thread in each of a plurality of plain knitted panels, wrapping a plurality of selected loops of the same course in each of said plain knitted panels including loops in the endmost wales of said panels so as to produce wrap effects separated only by the intervening rib knitted panels.

HENRY HAROLD HOLMES.
